US00D480685S

(12) **United States Design Patent** (10) Patent No.: **US D480,685 S**
(45) Date of Patent: **** Oct. 14, 2003**

(54) **ELECTRICAL CONNECTOR**

(75) Inventor: **Ken Hagiwara, Gunma (JP)**

(73) Assignee: **Hosiden Corporation, Osaka (JP)**

(**) Term: **14 Years**

(21) Appl. No.: **29/156,529**

(22) Filed: **Mar. 4, 2002**

(30) **Foreign Application Priority Data**

Sep. 3, 2001 (JP) 2001-025841

(51) LOC (7) Cl. **13-03**

(52) U.S. Cl. **D13/147**

(58) Field of Search D13/146, 147,
D13/154; 439/79, 108, 607, 610
